UNITED STATES PATENT OFFICE.

SALEMON AKRE, OF SEATTLE, WASHINGTON.

APPARATUS FOR HANDLING PURSE-SEINES.

1,390,006.

Specification of Letters Patent.

Patented Sept. 6, 1921.

Application filed October 25, 1920. Serial No. 419,848.

To all whom it may concern:

Be it known that I, SALEMON AKRE, a citizen of the United States, and resident of the city of Seattle, county of King, and 5 State of Washington, have invented certain new and useful Improvements in Apparatus for Handling Purse-Seines, of which the following is a specification.

My invention relates to apparatus employed in handling purse seines to and from the boats.

The object of my invention is to provide a device whereby the threading of the purse line within the purse rings may be more expeditiously performed and with less labor and one which will in other ways facilitate the handling of the purse seine while taking it in and while running it out.

The features of my invention which I believe to be new and upon which I desire to obtain a patent will be hereinafter described and then particularly pointed out in the claims.

In the accompanying drawings I have shown my device embodied in the type of construction which I now prefer to use and one which illustrates the principle of my invention.

Figure 1 shows, in plan view, the general arrangement employed upon a boat in handling the purse seine, together with my special apparatus.

Fig. 2 is a side elevation of the same parts, showing the novel means I employ for handling the purse rings and the purse line.

Fig. 3 is a vertical section taken through the standard of my apparatus.

Fig. 4 is a cross section taken through the tubular finger upon which the purse rings are placed.

Fig. 5 shows an outer end view of the standard and the finger which carries the ring-holding finger and Fig. 6 is a side view of one of the finger-supporting struts or braces.

The usual plan of handling a purse seine when paying it out, is to thread the purse line through the rings of the seine by hand. This is a slow operation and interferes with 50 the speed of handling of the seine. It also is laborious work and requires additional hands to do it. By my present invention the threading of the purse line through the purse rings is automatically accomplished 55 and the seine may therefore be run out as

fast as it is possible to discharge it from the boat and haul it away. In consequence, the operation of the purse seine is much facilitated and speeded up and also a great deal of laborious hand labor is eliminated. 60

In the drawings Fig. 1 illustrates a net being paid out from a platform, as 1, which is mounted upon the stern of the boat 7 as a turntable, the same being turnable about a central pivot 10 and supported upon rollers 65 71 so that the seine may be fed off from the boat toward either side or stern, or at any intermediate angle. This is at present a standard equipment.

Mounted upon this turntable is a long finger or arm 2 which is supported entirely from one end and at such an elevation above the turntable as to enable it to conveniently receive and support the purse rings 3 of the purse net. This finger or arm is of a size 70 75 to receive these rings and yet to permit free sliding of the rings thereupon so that when the net is paid out the net itself may pull the rings off of the finger.

The finger 2 is secured by one end to a 80 supporting standard or frame 20. The length of this finger should be sufficient to accommodate all of the rings of the net. It is, of course, possible to employ two of these fingers and to place substantially half of 85 the rings upon one finger and the other half upon the other finger, but where possible to do so, I prefer to employ one finger for holding all of the rings, as this simplifies the work and avoids complication. 90

The ring holding and storing finger or arm 2, is so constructed that the purse line 4 may be placed lengthwise of said finger and within the purse rings 3 and yet be supported out of engagement with said rings so 95 that, as the purse line is drawn out through the outer or unsupported end of the finger, it will not engage with the rings so as to cause them to be drawn off. The rings 3 are drawn from the finger by means of the lines 100 11 which connect them directly with the seine. It is the pull of the seine itself which draws the rings from this finger. They are, therefore, drawn off one at a time. As the purse line 4 is supported by the finger 2 and 105 extends through all of the rings 3, it follows that as the net is paid out the purse line will be found within the rings.

For convenience in placing and removing the purse line the finger 2, as well as a por- 110

tion of the post or standard 20, may be provided with a side opening, as shown at 21. This opening forms a slit of a size to freely pass the purse line, which slit extends the full length of the tube 2 and a portion of the upper end of the standard which is in alinement with this tube. Therefore, when the tube is free of the purse rings, the purse line may be passed through this slit in the tube. In taking in the net, the body thereof is piled upon the turntable 1 and the rings as they come in are threaded by hand upon the finger 2.

In order to furnish a better support for the overhung body of the finger 2, I may provide removable struts or braces 5, which are supported from the turntable and engage the lower side of the finger 2, but in such manner that they may be readily thrown down by the pull of the ring 3 which is next back therefrom as the net is paid out. A suitable and preferred type of construction for these struts is shown in Fig. 6 which consists of a bar provided with a saddle or seat 50 at its upper end and adapted to engage with the ring-carrying finger 2, and at its lower end hingedly connected with the turntable. A preferred type of support for the lower end is a slotted inverted cup 51 in the slot of which is placed the rod, a collar 52 forming the supporting bearing and a knob 53 preventing removal of the bar. As many struts of this sort may be provided as is desired. These will support the weight of the finger when the latter is loaded with the rings and are readily removable by the rings as these are drawn therefrom.

The finger 2 may be made by rolling a sheet of metal into tubular form of a size such that the edges thereof are separated a sufficient distance to provide the side opening 21 through which the purse line 4 may pass, or by cutting a slot from an ordinary tube. If it be desired to additionally strengthen this tube, a reinforcing web, as 22 may be secured within the tube.

At the inner or supported end of the tube 2 I prefer to provide one or more guide pulleys, as 23, so that the line may pass from this standard to a holding device such for instance, as a capstan head 6 which is located at any convenient point on the deck, thereby permitting application of power to this work. The purse line, after being drawn in, is coiled as at 40 or otherwise

disposed of in any suitable manner which will permit it to be freely run out when the net is being paid out.

In preparation for running out the net, an end of the purse line is passed through the arm 2 and all of the rings carried thereby and then secured to the net. As the net is run out the purse line is thus drawn into all the purse rings.

By means of the above device it is possible to satisfactorily run the net out as fast as it is possible to pull it out by the boats or whatever means are employed for this purpose and to insure that the purse line is satisfactorily threaded through the rings.

What I claim as my invention is:

1. A device for threading purse lines into purse seines comprising a tubular finger supported from one end and adapted to receive the pursing rings thereon and the purse line therein.

2. A device for threading purse lines into purse seines comprising a tubular finger supported from one end and adapted to receive the pursing rings thereon and the purse line therein, and having a slot extending lengthwise thereof adapted to permit passage of the purse line.

3. A device for threading purse lines into purse seines comprising a tubular finger supported from one end and adapted to receive the pursing rings thereon and the purse line therein, and struts adapted to support said finger and to be pulled out by the pursing rings.

4. A purse line threading device for purse seines comprising a tubular finger supported in horizontal position from one end and having a slot in one side adapted to pass the purse line, said tube being of a size to freely pass the pursing rings thereover, and supporting struts for the overhanging parts of said finger adapted to be disengaged therefrom by the pull of the pursing rings.

5. The method of threading pursing lines in seines which consists in assembling and supporting all the pursing rings together in alinement when piling the net and supporting the purse line within and independently of all of said rings, whereby the purse line may be drawn through the rings as the net is run out.

Signed at Seattle, Washington, this 18th day of October, 1920.

SALEMON AKRE.
